UNITED STATES PATENT OFFICE.

EWDOKIJA MIKOLYN, OF CHARLEROI, PENNSYLVANIA.

CURTAIN-POLE AND WINDOW-SHADE HOLDER.

1,346,233.

Specification of Letters Patent. Patented July 13, 1920.

Application filed October 23, 1918. Serial No. 259,396.

To all whom it may concern:

Be it known that I, EWDOKIJA MIKOLYN, a Ukrainian, claimed as subject of the Emperor of Austria, residing at Charleroi, in the county of Washington and State of Pennsylvania, have invented certain new and useful Improvements in Curtain-Pole and Window-Shade Holders, of which the following is a specification.

10 The primary object of the invention is the provision of a supporting means for shade rollers and curtain poles readily attached to a window casing without the employment of screws or nails ordinarily inserted in the inner face of a casing, the device being readily adjustable for accommodating poles and shade rollers of different lengths and being easily detached from the window casing whenever desired.

20 A further object of the invention is to provide a shade roller and curtain pole holder that possesses great strength, is easy and inexpensive to manufacture, and by means of which a roller and a pole may be quickly mounted upon a window casing without in any manner mutilating the front face thereof, the device also presenting a neat and artistic appearance.

With these general objects in view the invention consists in the combination and arrangement of parts hereinafter fully described as well as illustrated in the accompanying drawings.

In the drawings like reference characters 35 designate corresponding parts throughout the several views, and in which—

Figure 1 is an elevational view of a portion of the upper part of a window casing with one of my holders mounted thereon, a 40 curtain pole and a shade roller being indicated by dotted lines in their assembled relations,

Fig. 2 is a vertical sectional view taken upon line II—II of Fig. 1, with the pole and roller with its shade shown in full lines,

Fig. 3 is a horizontal sectional view taken upon line III—III of Fig. 1 with the curtain pole indicated by dotted lines,

Fig. 4 is a horizontal sectional view similar to that shown in Fig. 3, taken upon a plane below the pole supporting means and illustrating a shade roller by means of dotted lines,

Fig. 5 is a perspective view of the lower section of the holder and

Fig. 6 is a similar view of the upper section thereof.

Referring more in detail to the drawings, my invention broadly consists of a bracket having a lower shade roller supporting portion or section 10 and an upper curtain pole supporting section 11, the two sections being assembled together and secured upon the top or cross piece 12 of a window casing in the manner hereinafter described, it being understood that two of the brackets are employed when the invention is in use, suitably spaced apart for accommodating a shade roller and curtain pole of any suitable length.

The section 10 comprises a plate 13 adapted for flatly engaging the forward face of the top piece 12 and has a sharpened angular flange 14 at its lower edge for engaging the lower edge 15 of said top piece 12. An upwardly projecting reduced portion 16 of the plate 13 terminates in a threaded shaft or bolt 17 projecting above the upper edge 18 of the top piece 12 when the holder is positioned thereon.

The roller holding section 11 consists of a plate 19 slidably mounted upon the plate 13 between opposite forwardly projecting guides or flanges 20 of the plate 13, while a substantially L-shaped flange 21 at the top 85 of the plate 19 has a central perforation 22 through which the bolt 17 is freely positioned. The free edge portion 23 of the flange 21 is sharpened for cutting into the upper edge 18 of the top piece 12 when the sections 10 and 11 are drawn together by means of a thumb nut 24 threaded upon the bolt 17 and adapted to bear against the flange 21. It will be evident that when the plate 13 flatly engages the top 12 with the plate 19 90

slidably positioned upon the plate 13 with the sharpened flanges 14 and 23 positioned beneath and above the top piece 12, the turning of the nut 24 downwardly upon the bolt 17 in contact with the flange 21 forces said edges 14 and 23 into firm holding contact with the lower and upper edges 15 and 18 respectively of the top piece 12 of the window casing. In this manner, my holder is secured at any desired position upon the top 105 piece of a window casing without mutilat-

ing the forward face of the top piece and in a manner permitting the ready adjustment as well as removal of the holder whenever desired.

5 An arm 25 is carried substantially centrally by the plate 13 and projects outwardly thereof, having a notch 26 adapted to receive the terminal pintle 27 of a shade roller of the usual construction such as 28 10 for mounting the shade 29 thereof in a serviceable position forwardly of the window casing.

A bracket 30 is secured to the plate 19 of the upper section 11 provided with a U-shaped socket 31 within which a curtain pole 32 may removably rest. The bracket 30 is at one side of the center of the plate 19 and arm 25 being centrally of the plate 13, this arrangement permits better access 20 to the arm in manipulating the shade roller. The arm 25 and bracket 30 are secured to the plates 13 and 19 respectively in any desired manner such as by integral rivets or holdfast means 33 secured through the respective plates, it being only essential that such holdfast means do not project rearwardly of the plates so as to interfere in any manner with the flat engagement of the plate 13 with the top piece 12 or the sliding engagement of the two plates 13 and 19. 25 When two of the holders are secured to the top piece 12 of a window casing, a curtain

pole 32 may be readily positioned within the sockets 31 of the brackets 30 thereof, while a shade roller 28 may be readily attached in 35 the usual manner to the opposite arms 25.

What I claim as new is:—

A bracket of the class described comprising vertically disposed inner and outer overlapping plates, outwardly-turned guide 40 flanges formed on the sides of the inner plate slidably securing the plates together, the outer ends of the plates being provided with inwardly-turned portions and securing members projecting from the inwardly-turned 45 portions adapted to engage the edges of the casing, the inner plate being in flat contact with the casing to guard against lateral tilting of the bracket, a partly flat and partly screw-threaded shank on the inner plate extending through the inwardly-turned portion of the outer plate and disposed in flat contact with the casing, a nut on the screw-threaded 50 part of the shank adapted to be screwed against the outer face of said last-named inwardly-turned portion, and a shade or curtain supporting member carried by one of 55 said plates.

In testimony whereof I affix my signature.

EWDOKIJA ^{her} X MIKOLYN.
